UNITED STATES PATENT OFFICE.

OLIVER G. BRADY, OF NEW YORK, N. Y.

IMPROVEMENT IN PEAKS OR BRIMS FOR HATS OR CAPS.

Specification forming part of Letters Patent No. **222,418**, dated December 9, 1879; application filed October 15, 1879.

To all whom it may concern:

Be it known that I, OLIVER G. BRADY, of the city, county, and State of New York, have invented certain new and useful Improvements in Peaks or Brims for Hats or Caps, of which the following is a specification.

My invention relates most particularly to caps or hats to be worn by railroad train-men, firemen, and others who are compelled to face strong winds or currents of air loaded with dust, sparks, or snow; and it consists in a peak or brim made wholly or in part of glass, mica, or other transparent material.

The object of my invention is to provide a peak that will protect the face and eyes of the wearer against injury from strong currents of air, and the dust and particles borne by the same, and at the same time not offer any material obstruction to his vision.

In carrying out my invention I may construct the peak entirely of mica, glass, or other similar transparent material. Such a peak is shown in Figure 1 of the drawings, which serve to illustrate my invention. If it is desired to construct a peak which will shade the eyes to a degree, and also permit the wearer to see objects through it, the glass or other material employed may be tinted, or the body may be tinted and portions be left transparent or untinted, so that objects may be seen with greater distinctness.

In some cases the peak may be made of leather or other opaque material, and plates or panes of glass, mica, or other transparent substance be set in openings cut through the same at points corresponding to the position of the wearer's eyes. Peaks constructed in this manner are illustrated in Figs. 2 and 3, the former showing two elliptical windows, *a a*, set in a peak, *A*, of opaque material, and the latter an opaque peak provided with an elongated window. I prefer the construction shown in Fig. 2, for the reason that the peak, as a whole, is stronger and the smaller windows less liable to be broken, while the range of vision is not materially limited.

A peak constructed according to my invention may be affixed to the cap in the usual way, and may be applied so as to project at any angle; but as it does not obstruct the vis-

ion it may be somewhat inclined normally, so as to protect the face and eyes from flying particles.

Although especially adapted to the peaks of caps, my invention may also be applied to the brims of hats, as shown in Fig. 4, in which *B* represents the crown of a fireman's hat, and *C* the brim at the back, provided with transparent windows *a a*. The hat thus provided may be turned and worn hind part before, when the exigencies of the case demand it, and the wider portion of the brim will then protect the face, while the vision is not obstructed.

Where the peak is made wholly of transparent material—as mica, for instance—it may be bound at the edge with leather, metal, or other material, as shown at *b*; and where windows are inserted they may be secured in any well-known manner. Where two thicknesses of leather, bound at the edges, are employed to form the peak, the transparent plate or pane may be set between them; or the panes may be provided with frames, or be set in rabbets recessed into the material of the peak or brim.

In some cases I contemplate employing lenses for windows, and especially for near-sighted persons, where magnifying-lenses may be employed to good advantage. The windows *a a* in Fig. 2 may be considered as representing either plain windows or magnifying-lenses.

I am fully aware that masks or hoods to be drawn over the face have been provided with windows, and that windows have been placed in the flexible crown of a hat or head-covering, which might be brought before the eyes by pulling the crown down over the face; but these do not answer the purpose contemplated by my invention. They shroud and muffle the face, tend to impede respiration, are hot and uncomfortable, and do not serve the purpose of a hat or cap for common wear. My improved peak may be attached to and form a part of the ordinary cap, and the cap so provided may be worn in the ordinary way; but when the head is bent forward so that the peak will shield the face to a degree, the wearer may obtain a view through the peak by simply rolling the eyes upward.

I am also aware that it is old to attach an eyeglass or glasses by its frame or stem to a hat or cap, and I make no claim to this; but

What I do claim is—

1. A peak or brim for a cap or hat, composed wholly or in part of transparent material, substantially as and for the purposes set forth.

2. A peak or brim for a cap or hat, constructed of opaque or non-transparent material, and provided with a transparent window or windows set into the same, substantially as shown, for the purposes set forth.

3. A peak or brim for a cap or hat, provided with magnifying-lenses set into the same, substantially as and for the purposes set forth.

In witness whereof I have hereunto signed my name in the presence of two subscribing witnesses.

OLIVER G. BRADY.

Witnesses:
